Claims priority, application Great Britain
February 16, 1951

9 Claims. (Cl. 179—18)

The present invention relates to automatic exchanges in which a plurality of communication channels is provided by means of a plurality of time interlaced pulse trains, and, in operation, when establishing communication between two stations connected to the exchange, apparatus associated with a first station selects a free channel terminating unit, a signal is transmitted to automatic switching apparatus associated with the second station identifying the selected channel, and the said automatic switching apparatus connects the second station to the identified free channel. Such automatic exchanges will be referred to hereinafter as "automatic exchanges of the kind specified" and examples of such exchanges are disclosed in co-pending U. S. patent applications Nos. 247,072 filed the 18th September 1951, 257,786 filed the 23rd November 1951 and 257,991 and 257,992 filed the 24th November 1951.

The present invention is concerned to provide a suitable channel terminating unit for use in an automatic exchange of the kind specified.

According to the present invention a channel terminating unit for use in a automatic exchange of the kind specified, comprises means for applying impulses to a first output terminal for connection to a register in response to the application of impulses to a first input terminal, a second input terminal for connection to a source of gating pulses, two gate devices, connections between the second input terminal and the two gate devices to cause the gate devices to open only when gating pulses appear at the second input terminal, means for applying speech or other signals from the first input terminal through one of the gate devices to a second output terminal, means for applying pulses appearing at a third input terminal to the second gate device to be gated by the said gating pulses, and a pulse demodulator connected between the output of the second gate device and the first input terminal.

The invention will now be described by way of example with reference to the accompanying drawing in which—

Figure 1 is a block schematic diagram of an automatic telephone exchange of the kind specified embodying a channel terminating unit according to the present invention.

Figure 2 is a circuit diagram of one embodiment of the invention suitable for use in the automatic exchange of Figure 1.

Figure 1 is a block schematic diagram of an automatic telephone exchange which is fully described in the specification of co-pending patent application No. 257,786 filed November 23, 1951. This exchange will not therefore be fully described in the present specification.

The telephone exchange shown in Figure 1 is suitable for use with 2000 subscribers. Of the 2000 subscribers stations connected to the exchange, one is shown at 10 and another at 11, the station 10 being terminated in the exchange at "subscribers line circuit" 12 and the

station 11 being terminated at the "subscribers line circuit" 13.

The exchange comprises a group of 100 pulse communication channels the pulses in each channel having a recurrence frequency of about 8,000 P. P. S. This group of channels is provided by means including a pulse generator 14 adapted to generate pulses suitable for combination to provide the 100 channels time-interlaced at the pulse repetition frequency of 8,000 P. P. S. in each channel. The 100 channels are terminated by 100 "calling units" respectively of which one is shown at 15. 100 "called units" terminate the other ends of the channels respectively when in use, one of the "called units" being shown at 16. Messages between the calling and called units pass through a "go speech junction" 17, a "return speech junction" 18 or a "metering and release junction" 19 as the case may be. In the event of a called subscriber being engaged a "busy signal" is transmitted to the calling subscriber by way of a "busy junction" 20.

For use in establishing calls between subscribers, a number of alloters 24 and registers 23 are provided together with a signalling junction 25 and two further pulse generators 21 and 26.

Assuming the subscriber at the station 10 to be calling the subscriber at the station 11 the first operation occurs in the subscribers line circuit 12. This contains a finder which finds a free calling unit 15. An allotter 24 then comes into operation and allots a register 23 to the calling unit 15.

By means of the allotter and a finder in the register the calling unit found by the subscribers line circuit 12 is connected to the allotted register 23. A dialling tone is then automatically transmitted to the calling subscriber.

The output of the pulse generator 21 is in the form of a recurring sequence of 20 pulses which for convenience will be divided into groups of ten each. The first ten pulses in each sequence will be referred to collectively as the *d'* pulses and the second ten as the *u'* pulses. The ten *d'* pulses will be referred to individually as the pulses *d'*₀ to *d'*₉ respectively and appear at the terminals *Td'*₀ to *Td'*₉ respectively of the generator 21. The ten *u'* pulses will be referred to individually as pulses *u'*₀ to *u'*₉ and appear at the terminals *Tu'*₀ to *Tu'*₉ respectively of the generator 21.

Each of the calling units 15 is connected to one of the terminals *Td'*₀ to *Td'*₉ and to one of the terminals *Tu'*₀ to *Tu'*₉ of the generator 21, different ones of the calling units being connected to different pairs of the terminals *Td'* and *Tu'*. Thus each calling unit is identified by a different pair of *d'* and *u'* pulses and, as will be described later, the pair of *d'* and *u'* pulses identifying the calling unit, and hence the selected channel, is transmitted to the called subscribers line circuit to identify the high grade channel on which communication is to be established.

When the calling subscriber hears the dialling tone and dials the number of the called subscriber, the dialling pulses are transmitted through the line circuit 12 and the seized calling unit 15 to the allotted register 23. In the register the four sets of dialling pulses are stored on four uniselectors. Four groups of ten pulses each, which will be referred to as the M, C, D and U pulses, are applied to the four uniselectors in the register from the pulse generator 26. Thus the uniselectors in the register select one pulse from each of the four groups of recurring pulses applied thereto and it is arranged that these four selected pulses are combined to form a recurring output pulse which occurs in one recurring channel interval in a recurring sequence of 2,000 channel intervals. The sequence may recur for example at the

rate of one per second and the 2,000 channels constitute a group of low grade signalling channels.

The recurring output pulse from the register is used as a gate pulse and permits the recurring pair of $d' u'$ pulses identified with the seized calling unit to pass to a signalling junction 25 only in the low grade channel interval determined by the gating pulse.

The output from the signalling junction is applied to all subscribers line circuits. These circuits have gating pulses applied thereto however from the pulse generator 26, the gating pulses applied to each subscribers line circuit being in the channel whose number corresponds to the subscriber's number on the exchange. Thus the only subscribers line circuit to respond to a pair of $d' u'$ pulses appearing at the output of the signalling junction is that one whose gating pulse corresponds to the number dialled.

The called subscribers line circuit then hunts for a free called unit and when a free called unit is found this unit functions to select appropriate pulses from the output of the generator 14 to enable the called subscriber to establish communication in the channel terminated by the seized calling unit. The calling unit forms the subject of the present invention and one embodiment thereof will now be described in more detail with reference to Figure 2.

In Figure 2 terminals $+O_1$, $-O_1$, and PO_1 are for connection to the subscribers line circuits of which two are shown in Figure 1, and the terminals $+O_1$ and $-O_1$ are extended through a subscribers line circuit when in use to the subscribers line. The terminal $+O_1$ is connected through relay contacts D_1 and one winding of relay A to earth. Terminal $-O_1$ is connected through relay contacts D_2 , a second winding of relay A and a battery BAT_3 to earth. Terminals $+O_1$ and $-O_1$ are also connected through capacitors C_1 and C_2 respectively to a winding MW_1 of a hybrid transformer HY_1 which has a balancing resistor RB . The function of the hybrid transformer and balancing resistor is as described on page 83 vol. I of Telephony by Atkinson, published by Sir Isaac Pitman & Sons Ltd., London and New York.

The winding OW_1 of the hybrid transformer is connected through a capacitor C_3 to the control grid of a pentode valve V_4 whose anode is connected through a load resistor R_3 to the positive terminal PB_2 of a source (not shown) of D. C. whose negative terminal is earthed. The cathode of the valve V_4 is earthed, the screen grid is connected directly to the terminal PB_2 , and the suppressor grid is connected through a resistor R_4 to the negative terminal $-GB_1$ of a bias source (not shown) whose positive terminal is earthed. The suppressor grid is also connected through a capacitor C_4 and relay contacts B_5 to a terminal GP . The anode of the valve V_4 is connected through a capacitor C_5 to a terminal GSP_1 .

Winding IW_1 of the hybrid transformer HY_1 is connected to the output of a low-pass filter FIL_1 . One input terminal of the filter is connected to the anode of a pentode valve V_3 and the other to earth through a capacitor C_6 and through a resistor R_5 to the positive terminal PB_3 of a source of D. C. (not shown). The suppressor grid and cathode of the valve V_3 are connected to earth.

A terminal $RSPO_1$ is connected through a capacitor C_8 to the control grid of a pentode valve V_5 whose cathode is earthed. Negative bias is applied to the control grid of the valve V_5 from the negative terminal $-GB_{20}$ of a bias source (not shown) whose positive terminal is earthed. The anode of the valve V_5 is connected through the primary winding of a transformer XF_1 to the positive terminal PB_4 of a source (not shown) of D. C. whose negative terminal is earthed. The screen grid of the valve V_5 is connected directly to the terminal PB_4 and the suppressor grid is connected through a resistor R_6 to the negative terminal $-GB_3$ of a bias source (not shown) whose positive terminal is earthed. The suppressor grid of the valve V_5 is also connected through a capacitor C_9 and the contacts B_5 to the terminal GP .

The transformer XF_1 has two secondary windings

5 S_1XF_1 and S_2XF_1 . One terminal of winding S_1XF_1 , is connected to the negative terminal $-GB_2$ of a bias source (not shown) and the other terminal is connected through a rectifier W_5 , and a resistor R_7 to the control grid of the pentode valve V_3 and is connected through a rectifier W_3 to the negative terminal $-GB_4$ of a bias source (not shown) whose positive terminal is earthed. One terminal of the winding S_2XF_1 is connected to the negative terminal $-GB_4$ and the other terminal of the winding S_2XF_1 is connected through a rectifier W_6 to the control grid of the valve V_3 . The terminal $-GB_4$ is also connected to the control grid of V_3 through a rectifier W_4 and a capacitor C_{10} is connected between the control grid of V_3 and earth.

10 15 A terminal $ASPO_1$ is connected through a rectifier W_7 and capacitor C_{11} to the control grid of a triode valve V_6 whose cathode is earthed and whose anode is connected through a relay winding D to the positive terminal PB_5 of a D. C. source (not shown) whose negative terminal is earthed. The control grid of the valve V_6 is also connected through a rectifier W_8 to the negative terminal $-GB_5$ of a bias source (not shown) whose positive terminal is earthed. The junction of the capacitor C_{11} and the rectifier W_7 is connected to the terminal GP through a resistor R_8 .

20 25 A relay winding J has one terminal connected to earth through a battery BAT_4 . The other terminal of the relay winding J is connected to earth through relay contacts D_3 , a busbar BUS_1 and relay contacts B_4 . The busbar is connected through relay contacts E_1 , one winding of relay E and a battery BAT_5 to earth. A control terminal P_1 is connected either directly to earth or through the other winding of relay E and a battery BAT_6 to earth depending upon the setting of relay contacts B_3 and E_3 . The busbar BUS_1 is connected through relay contacts G_1 , one winding of a relay G and a battery BAT_7 to earth. The other winding of the relay G has one terminal connected to earth through a battery BAT_8 , and has its other terminal connected directly to a terminal BU_1 . The busbar is also connected through relay contacts E_2 to an output terminal AL .

30 35 Terminal HO is connected through relay contacts D_5 , E_4 and A_1 to earth. A relay winding B has one terminal connected through contacts A_1 to earth and the other through a battery BAT_9 to earth. An output terminal IMP is connected through relay contacts B_2 and A_1 to earth.

40 45 Input terminals $Td'u'$ and $Tu'u'$ are connected together through resistors R_9 and R_{10} and the junction of these two resistors is connected through relay contacts E_6 to an output terminal $Rd'u'$.

50 55 Terminal PO_1 is connected through relay contacts B_1 to relay contacts D_4 which depending upon their setting, provide either an earth connection or a connection to relay contacts J_1 . The relay contacts J_1 provide either an earth connection or a connection through a resistor R_{11} and a battery BAT_{10} to earth.

60 65 The cathode of a gas-filled triode valve V_2 is connected to earth through relay contacts A_2 and its anode is connected through a relay winding F to the positive terminal PB_6 of a suitable source (not shown) of D. C. whose negative terminal is earthed. A capacitor C_{12} is normally connected to the positive terminal PB_7 of a source (not shown) of D. C. whose negative terminal is earthed. The control grid of the valve V_2 is connected to the capacitor C_{12} through a resistor R_{12} and the contacts E_5 .

70 75 A source (not shown) of busy tone is connected to the terminal BT which is connected to the centre winding of the relay A through relay contacts G_2 .

A source (not shown) of dialling tone is connected to the terminal DT which is connected through relay contacts F_1 to the centre winding of the relay A .

When the calling unit is not in use there is no earth on the terminal PO_1 , the contacts B_1 being open. The absence of an earth on this terminal serves to indicate to a

searching subscribers line circuit that the calling unit is available for use. When the calling unit is seized by the subscribers line circuit current flows from earth through the left-hand winding of the relay windings A, through the relay contact D₁, through the calling subscriber's line, back through the relay contacts D₂, through the right-hand winding A and through the battery BAT₃ to earth. Thus the relay A operates and its contacts A₁ and A₂ close.

The contacts A₂ apply an earth to the cathode of the gas-filled triode V₂, and hence prepare this valve for later operation.

The contacts A₁ complete the circuit of the relay winding B the circuit being from earth through the battery BAT₉ through the winding B and the contacts A₁ to earth. The relay contacts B₁ to B₅ close. The contacts B₁ apply an earth to the terminal PO₁ thus indicating to any further searching subscriber's line circuit that the calling unit is engaged. The contacts B₂ prepare a circuit for transmitting subsequent dialling impulses to the terminal IMP. The contacts B₃ connect the terminal P₁ to the contacts E₂ and thence through the left-hand relay winding E to the negative terminal of the battery BAT₆. The contacts B₄ put an earth on the busbar BUS₁. The contacts B₅ connect the terminal GP to the suppressor grids of the two valves V₄ and V₅.

It is assumed that the seized calling unit terminates channel No. 1. The high-frequency pulses d_0 and u_1 from the pulse generator 14 of Figure 1 are therefore applied to the calling unit at T_{d0} and T_{u1} from the terminals of like reference in Figure 1. The rectifier W₆₆ provides a low impedance path for all of each d_0 pulse applied to the terminal T_{d0} except that part thereof which occurs during a u_1 pulse. The u_1 pulses render the rectifier non-conducting. Thus during the absence of the u_1 pulse the d_0 pulse applied to the terminal T_{d0} is dropped across the resistor R₁₇₉. During each u_1 pulse coincident with a d_0 pulse, however, voltage is passed to the terminal GP.

The voltage pulses appearing at the terminal GP are arranged to be positive-going. The negative bias applied to the suppressor grids of the two pentodes V₄ and V₅ is arranged to be sufficient to render these two valves normally non-conducting. The amplitude of the voltage pulses applied to the suppressor grids of the two pentodes V₄ and V₅ from the terminal GP is arranged to be sufficient to overcome the bias and to render these two valves conducting. Thus the valves V₄ and V₅ are gated in channel No. 1, and unmodulated pulses in channel No. 1 are transmitted from the anode of V₄, through the capacitor C₅ to the terminal GSP₁.

The earth applied to the terminal A₁ through contacts B₄, the busbar BUS₁ and the contacts E₂ is for the purpose of allotting the register to the calling unit as described in co-pending patent application No. 257,786. When the register is allotted the terminal P₁ becomes earthed through the register and hence the relay E becomes energised. The contacts E₁ are hold-on contacts and are arranged to close before any other contacts of the relay E. Operation of the relay contacts E₂ and E₃ serves to release the allotter as described in co-pending patent application No. 257,786. The contacts E₄ complete a circuit from earth through the contacts A₁, E₄ and D₅ to the terminal HO. The earth and the terminal HO serve to hold the allotted register as described in copending patent application No. 257,786. The contacts E₅ connect the charged capacitor C₁₂ to the control grid of the valve V₂ which therefore strikes and energises the relay winding F. The contacts F₁ close and hence dialling tone is fed to the calling subscriber's line through the winding of the relay A and the calling subscriber's line circuit.

The contacts E₆ connect the terminals T_{d0} and T_{u1} to the terminal R_{d0} and R_{u1}. The low frequency pulses d_0 and u_1 are applied to the terminals T_{d0} and T_{u1} respectively and hence appear at the terminal R_{d0} and R_{u1}.

These low frequency pulses are employed in the exchange to identify to the called subscriber the channel number of the calling unit seized by the calling subscriber. In this example the low frequency pulses indicate that channel No. 1 has been seized.

When the calling subscriber dials the number he requires the dialling impulses operate the relay A, one operation of the relay A occurring for each dialling impulse. The operation of the contacts A₁ serves to transmit corresponding impulses to the terminal IMP which is connected to the allotted register.

When the called unit 16 (Figure 1) seized by the called subscriber's line circuit is set up in the identified channel (channel No. 1 in this example) pulses are transmitted from the called unit through the metering and release junction 19 (Figure 1) to the terminal ASPO₁ in Figure 2. Each of these pulses renders the rectifier W₇ non-conducting and hence the pulses appearing in channel No. 1 at the terminal GP are permitted to pass to the control grid of the valve V₆. This valve then passes pulses of anode current through the relay winding D which becomes energised.

The contacts D₁ and D₂ operate and reverse the polarity of the terminals +O₁ and -O₁. This is for signalling purposes as described on page 278 of Telephony vol. II by Atkinson. The contacts D₄ apply a pulse of current to the terminal PO₁ from the battery BAT₁₀, the relay contacts J₁ being operated after the contacts D₄ on de-energisation of the slow operating relay J by the opening 30 of the contacts D₃.

The pulse of current applied to the terminal PO₁ serves to operate the meter in the subscriber's line circuit as described in co-pending application No. 257,786. The contacts D₅ open and hence remove the earth from the 35 terminal HO. Thus the register is released.

Speech voltages from the calling subscriber's station are transmitted through the transformer HY₁ to the control grid of the valve V₄ and there amplitude-modulate the pulses in channel No. 1 applied to the terminal GP. 40 These amplitude-modulated pulses pass through the go speech junction to the called units.

Return speech appears in the form of modulated pulses in channel No. 1 at the terminal RSPO₁ and are applied to the control grid of the pentode V₅ which is gated by pulses in channel No. 1 applied to the suppressor grid 45 from the terminal GP.

The transformer XF₁ in the anode circuit of the valve V₅ together with the capacitors C₇ and C₁₀, the resistors R₇ and R₁₉₅ and the rectifiers W₃ to W₆ serve to broaden the pulses passed by the valve V₅ and hence facilitate 50 demodulation. The broadened modulated pulses are passed through the valve V₃ and are demodulated by a low-pass filter FIL₁. The speech voltages are applied through the transformer HY₁ and the calling subscriber's line circuit to the calling subscriber's line.

It is arranged that in the event of the called subscriber being engaged an earth appears on the terminal BU₁ as described in co-pending patent application No. 257,786. The earth on the terminal BU₁ causes the relay G to become operated. The contacts G₁ hold the 60 relay G and the contacts G₂ apply the busy tone to the calling subscriber's line through the relay winding A and the calling subscriber's line circuit.

When a call is ended and the calling subscriber replaces his handset on its rest the energising circuit for the relay A is broken. The relay contacts A₁ return to their unoperated position, thus de-energising the relay B. The contacts B₁ remove the earth from the terminal PO₁ which results in the release of the calling unit.

Although an arrangement has been described in which the reply pulses appear at the terminal ASPO₁ it will be appreciated that the reply pulses may be transmitted through the return speech junction by making the reply pulses of opposite polarity to the speech pulses. The 75 reply pulses can then readily be distinguished from the

speech pulses and subsequently caused to operate the relay Ds.

We claim:

1. In an automatic exchange having a plurality of stations, a plurality of pairs of lines, each said pair of lines including an incoming line and an outgoing line, each said pair of lines having a different time displaced pulse characteristic and a register for locating a called station: a channel terminating unit for a pair of lines, said unit comprising a first input terminal for connection to a calling station, a second input terminal for connection to a source of time displaced gating pulses characteristic of the line to which the unit is connected, a third input terminal for connection to the incoming line of said pair of lines, said incoming line having modulated time displaced pulse signals, a first output terminal for connection to the register, a second output terminal for connection to the outgoing line of said pair of lines, means for applying impulses to the first output terminal upon the application to the first input terminal of pulses from a calling station, a first gate device, a second gate device, circuit means connecting the second input terminal to both said gate devices so as to open said gate devices only when predetermined time displaced gating pulses characteristic of said pair of lines are applied to the second input terminal, circuit means for applying speech and the like signals received from a calling station at the first input terminal to the first gate device and through said device to the second output terminal, circuit means for applying modulated time displaced incoming speech pulses appearing at the third input terminal to the second gate device to be gated by the said gating pulses, a pulse demodulator, circuit means connecting the output of the second gate device to the input of the pulse demodulator, and circuit means connecting the output of the pulse demodulator to the first input terminal.

2. A channel terminating unit as set forth in claim 1 wherein the means for applying impulses to the first output terminal upon the application to the first input terminal of pulses from a calling station comprises a relay including an energizing means and contacts, the energizing means being connected to the first input terminal and the contacts being connected to the first output terminal.

3. A channel terminating unit as set forth in claim 1 wherein each gate device comprises an electron discharge tube having an anode, a cathode, a control grid, a screen grid and a suppressor grid, wherein the gating pulses appearing at the second input terminal are applied to the suppressor grids of both tubes, wherein the means for applying speech and the like signals to the first gating device comprises a hybrid transformer having a secondary winding connected between the control grid and the cathode of the tube forming the first of the gate devices, and wherein the means for applying pulses appearing at the third input terminal to the second gate device comprises a circuit for applying the modulated time displaced incoming speech pulses to the control grid of the tube forming the second gate device.

4. A channel terminating unit as set forth in claim 1 wherein the pulse demodulator comprises a pulse lengthening circuit and a low-pass filter.

5. A channel terminating unit as set forth in claim 1 wherein there are provided a fourth terminal, a relay indicating that a reply signal has been received, said relay being operable by reply signals in the form of pulses of the same phase as those characterizing the pair of lines to which the channel terminating unit is connected, and a circuit means for applying the reply signals to said relay for energizing the same.

6. A channel terminating unit as set forth in claim 5 wherein the reply signals are in the form of pulses coincident with the gating pulses and the means for applying the reply signals to the relay constitutes a gate device which is gated by said gating pulses.

7. A pulse channel terminating unit for use in an electronic telephone exchange, comprising a speech and signalling voltage terminal, a pulse modulator, a connection from said speech and signalling voltage terminal to said pulse modulator, a gating pulse input terminal connected to said modulator, a speech pulse output terminal, a connection from said modulator to said speech pulse output terminal, a speech pulse input terminal, a pulse gate, a connection from said speech pulse input terminal to said gate, a connection from said gating pulse input terminal to said gate to gate the speech pulses from said speech pulse input terminal, a speech pulse demodulator, a connection from the output of said gate to said speech pulse demodulator, a connection from the output of said demodulator to said speech and signalling voltage terminal, a signalling voltage regenerator, a connection from said speech and signalling voltage terminal to said signalling voltage regenerator, a signalling voltage output terminal, and a connection from the output of said signalling voltage regenerator to said signalling voltage output terminal.

8. A pulse channel terminating unit as claimed in claim 7, wherein said signalling voltage regenerator comprises a delay connected to be energized by signalling voltage applied thereto and having contacts connected to said signalling voltage output terminal.

9. A pulse channel terminating unit as claimed in claim 7, comprising a signalling reply pulse terminal, a further gate, a connection from said signalling reply pulse terminal to said further gate, a connection from said gate pulse input terminal to said further gate to gate signalling pulses applied thereto from said signalling reply pulse terminal, and means responsive to signalling reply pulses passed by said further gate to disconnect said signalling voltage regenerator from said signalling voltage output terminal.
